UNITED STATES PATENT OFFICE.

BERNARD H. ZIEHLER AND JAMES C. DAWLEY, OF DAYTON, OHIO, SAID DAWLEY
ASSIGNOR TO SAID ZIEHLER.

RECORDING-LOCK.

1,212,598.

Specification of Letters Patent. Patented Jan. 16, 1917.

Application filed October 28, 1914. Serial No. 868,739.

To all whom it may concern:

Be it known that we, BERNARD H. ZIEHLER and JAMES C. DAWLEY, citizens of the United States, residing at Dayton, in the county of Montgomery and State of Ohio, have invented certain new and useful Improvements in Recording-Locks, of which the following is a specification, reference being had therein to the accompanying drawing.

This invention relates to recording locks such as are sometimes used on stores, warehouses and other buildings where it is desirable that a record should be kept of the opening and closing of the doors.

The object of this invention is to provide a recording lock in which both the bolt and the recording device will be actuated by a knob or other suitable operating handle, and the operation of this knob or handle will be controlled by the key, thereby relieving the key of practically all work and enabling the heavier work of the operation of these parts to be accomplished by a knob or handle of sufficient size to enable it to be readily grasped and operated with comparatively small effort.

To this end it is a further object of the invention to provide a knob or operating handle which will be normally disconnected from the bolt and recording devices and the connection of which with the bolt and recording devices will be controlled by the key; further, to provide such a device in which the key will so control the recording mechanism as to cause a record to be made, when the knob is operated, which will identify the person operating the lock; to so arrange the mechanism that after the key has been inserted and the connection established between the knob and the bolt and recording mechanism it will be necessary to operate the knob to make a complete record before the key can be withdrawn.

It is also an object of the invention to provide a recording mechanism which will produce a record showing whether the lock was operated from the inside or the outside of the door and whether the bolt was moved into its locking position or its idle position.

A further object of the invention is to provide such a device which will be comparatively simple in its construction and 55 operation and moreover will be positive in

its operation, thereby insuring the making of the proper record upon each operation.

In the accompanying drawings, Figure 1 is a front elevation of a lock embodying the invention with the casing broken away; 60 Fig. 2 is a vertical, sectional view taken centrally of Fig. 1; Fig. 3 is a detail view of the operating mechanism for the connecting devices for the outside knob; Fig. 4 is a detail view of the actuating devices for the 65 key-identifying type wheel; Fig. 5 is an enlarged detail view of the clutch devices and the operating mechanism for the key-identifying device; and Figs. 6 and 7 are detail views of the key-actuated devices for the 70 key-identifying device.

In these drawings we have illustrated one embodiment of our invention and have shown the same as comprising a casing 1, the back wall, 2, of which forms a supporting frame upon which the greater part of the mechanism is mounted. The lock comprises a bolt 3 which may be of any ordinary or suitable construction and is here shown as a straight bar slotted to receive supporting pins 4 which permit the bolt to move through an opening 5 in that edge of the casing 1 adjacent to the edge of the door. The bolt is held in either its locking position or its retracted position by means 75 of pawls 6 which engage teeth 7 in the lower edge of the bolt. The teeth and pawls are so arranged that one pawl will hold the bolt against inward movement and the other will hold it against outward movement. 80 The bolt may be actuated in any suitable manner. Preferably it is provided with a projection, such as a pin 8, arranged to be engaged by one of two oppositely extending arms 9 and 10. In the present form of the 85 device these arms are integral and are in the form of a plate having its central upper portion cut away so as to provide the two arms at the opposite ends of the plate and provide the inner portions of the arms 95 with inclined surfaces. This plate is mounted on and rigidly secured to a shaft 11 by means of which the plate may be rocked in either direction. The plate from which the arms are formed is arranged close 100 to the pawl 6 and has projecting from that side thereof adjacent to the pawls pins 12 arranged close to the inner edges of the pawls so that when the plate is operated to move the bolt in one direction one of the 105 110

pins 12 will actuate that pawl which locks the bolt against movement in that direction, thereby releasing the bolt and permitting the further movement of the plate to bring the arm 9 into engagement with the pin 8 and thus actuate the bolt.

It will be noted that the arm 9 when in its normal position is spaced some distance from the pin 8 so that there is ample time for the releasing of the locking pawl before the arm engages the pin. The arm 10 would occupy the same relation to the pin 8 when the bolt has been moved into its outer position. The arms 9 and 10 also constitute the actuating devices for the recording mechanism. As here shown, the recording mechanism comprises a series of type wheels arranged in axial alinement. The several outermost type wheels, which are indicated at 13, are time and date wheels which may be adjusted in any suitable manner but as here shown the time wheels are connected with a clock mechanism 14 for positioning the same. Another of the type wheels, that shown at 15, is an identifying type wheel designed to identify the person, or rather the key, that operates the lock. The setting of this type wheel is controlled by the key and will be hereinafter described. The remaining type wheel 16 prints a mark on the record to indicate whether the lock has been operated to lock the door or to unlock the door and the setting of this type wheel will also be described presently. The recording device is here shown as comprising type wheels from which a record is printed but it will be understood that any suitable devices, from which a record may be taken, may be substituted for the type wheels. Arranged on one side of the type wheels is a support for a ribbon 17 and on the other side is a rewinding roll 18, the ribbon passing over suitable supports 19 arranged adjacent to the type wheels and serving to prevent the ribbon from dragging across the surface thereof. Arranged on one side of the type wheels and, in the present instance, above the same is a support for a roll of paper 20 and on the other side of the type wheels is a rewinding roll 21 provided with feeding mechanism for feeding the paper into and out of printing position with relation to the type wheels. As here shown the paper passes around rollers or guides 22 arranged adjacent to the type wheels to properly position the paper relatively thereto.

The operating mechanism for taking a record from the type wheels may be of any suitable character but preferably comprises rollers or platens 36 and 37 adapted to be moved across those portions of the type wheels which are in printing position, thereby forcing the paper and the ribbon against the type wheels and causing an impression to

be taken. In the present instance two platens are employed, these platens being arranged at the lower ends of two arms 23 and 24, which are preferably in the form of bell crank levers and are pivotally mounted on a stud 25. The upper ends of the arms are provided with projections or rollers 26 extending into the paths, respectively, of the arms 9 and 10, the outer portions of these arms being curved to form cams which will engage the rollers of the respective platen arms and actuate those arms to cause the platens to pass over the type wheels, it being understood, of course, that only one platen is operated upon each movement of the bolt. The arms or levers 23 and 24 are preferably acted upon by a spring 27 to hold the same normally in their retracted or inoperative positions and cams or guides 28 are arranged on opposite sides of the printing points of the type wheels to engage the supports for the platens and raise the latter out of engagement with the paper as soon as they have passed the printing point. The platens may be mounted on the lower ends of the arms in any suitable manner. As here shown they are journaled on the ends of short levers 29 which are pivotally mounted on the lower ends of the arms 23 and 24, respectively, and have their outer ends connected to the respective arms by means of springs 30.

The paper feeding mechanism may be controlled in any suitable manner but as here shown it is actuated directly from the arms 23 and 24. To this end a ratchet wheel 31 is rigidly secured to the rewinding roll 21 and is adapted to be engaged by either of two pawls 32 or 33. One of these pawls, 32, is carried by a lever 34 which is connected with the arm 23, and the other pawl, 33, is carried by a lever 35 which is connected with the arm 24. In each instance the arrangement is such that as the arms 23 and 24 return to their normal positions the pawl will operatively engage the ratchet wheel and actuate the rewinding roller to advance the paper.

The arms 9 and 10 which actuate both the bolt and the recording device are preferably operated by means of knobs, the term "knob" being here used to include any manually operated handle which may be used for this purpose regardless of its shape. As here shown a knob 41 is mounted on the inner end of the shaft 11 which is journaled in the casing 1 and, as above stated, is operatively connected with the arms 9 and 10. This knob being normally connected with the actuating devices it will be apparent that the bolt, and the recording devices, may be operated from the inside of the door at any time without the use of a key. A second knob 42 is mounted on the outside of the door and has a spindle 43 extending through

the door and rotatably supported therein. In the present instance this spindle extends into and is supported by the inner end of the shaft 11 which is hollowed out to receive it. This telescoping arrangement, however, constitutes only a support for the spindle or shaft 43 and does not constitute a connection between these shafts as either is free to rotate relatively of the other. Consequently, the knob 42 is normally disconnected from the bolt and recording devices and in order that these devices may be operated from the outside of the door it is necessary that a connection should be established between this knob and said devices. In the present instance this connection is established by connecting the shaft 43 with the shaft 11. To accomplish this a suitable connecting device or clutch is provided which will be actuated by the key, this being the only work performed by the movement of the key. While this connecting device may take various forms it is shown in the present drawings as comprising two disks 44 and 45, rigidly secured respectively to the shafts 11 and 43 and arranged close together. Each disk is provided in its edge with a notch 46, the notches being so arranged that when the two shafts are in their normal or idle positions the notches will be in alinement. A pin 47 is movably supported adjacent to the peripheries of the disks and is so mounted that movement may be imparted thereto by the key to move the same into the two notches, thus connecting the two disks one to the other and causing the shafts which carry the same to rotate in unison. In the present embodiment of the invention this pin is shown as mounted on a bar 48 which is slotted at its upper and lower ends to receive the shaft 43 and a shaft 49 arranged in alinement with the key barrel, as will be hereinafter described, thereby causing the bar to be guided in a substantially vertical line. The upper end of the bar is enlarged and has a substantially semi-circular slot 50 formed therein, said slot being of a width sufficient to receive the pin 47. The pin 47 is supported on the bar 48 by means of collars 51 spaced apart a distance sufficient to receive the bar between them and of a diameter greater than the diameter of the slot 50. Thus, the pin will be held in a substantially horizontal position with relation to the bar 48 but will be permitted to travel along the slot 50. When in its normal position the pin rests directly below the notches 46 in the disks and when vertical movement is imparted to the bar the pin will be carried into these notches, and the movement of the disks, when actuated by the knob 42, will carry the pin, while still in the notches 46, along one arm of the curved slot 50. Preferably, the inner end of the pin is guided in its

movement by flanges 52, there being preferably one of these flanges arranged adjacent to each arm of the slot 50 and so arranged that when the bar 48 is in its uppermost position the flanges will extend substantially parallel with the slot, thereby supporting the inner end of the pin and retaining the same in the notches 46 throughout its movement. The lower or adjacent ends of the flanges 52 extend downwardly and form a slot between them, as shown at 53, so that when the pin has been returned to its normal position, it, together with the bar 48, may move downward. These downwardly extending portions of the flanges also serve to hold the pin against lateral displacement when in its idle position.

As has been stated, the bar 48 is key-actuated to impart vertical movement to the pin 47. This may be accomplished in various ways. In the present instance I have employed a key 54 and key barrel 55 similar to those employed in the well known Yale lock. Arranged in alinement with the key barrel is a rotatable member which in the present instance, comprises the shaft 49. This shaft may be supported in any suitable manner but, in the present instance, it is hollow at one end and is rotatably mounted upon a shaft 56 which carries the key identifying type wheel 15 and which is journaled in the frame member 2. The hollow shaft 49 has an extension 57 provided with a slot 58 to receive the end of the key 54, which projects beyond the inner end of the key barrel, so that the shaft 49 will rotate with the key barrel when the key is in position. Rigidly secured to the shaft 49 is a cam 59 which is adapted to actuate the bar 48 and to this end is arranged to engage a pin 60 secured to the lower portion of the bar 48 and impart vertical movement to that bar when the key is rotated. The cam is so arranged that a partial rotation of the key will impart the desired movement to the pin 47 and is provided with a shoulder to engage the pin 60 and positively limit the forward movement of the key and its associated parts. Consequently, the key at the end of its turning movement always occupies the same position. Rigidly secured to the cam is a ratchet wheel 61 which co-operates with a pawl 62 to hold the ratchet wheel, and consequently, the key barrel and key 54 against rearward movement after its rotation has begun. The movement of the cam and the ratchet wheel is limited by a pin 63 arranged to engage a shoulder 64 on the ratchet wheel. The stop 63 co-operates with the pawl 62 to hold the ratchet and, consequently, the key rigidly in position after it has been rotated far enough to establish the connection between the outer knob 42 and the bolt and recording device. It is desirable that the key should be released

85

90

95

100

105

110

115

120

125

130

only after a record is made and the bolt is shifted. To this end the pawl 62 is connected with the lower end of a lever 65 pivotally supported between its ends and 5 having at its upper end a nose 66 arranged adjacent to the upper end of the bar 48 and adapted to be engaged by either one of two pins 67 which are carried by the disk 45. These pins are so arranged that when the 10 disk is rotated in either direction one of the pins will engage and actuate the lever 65, this engagement taking place during the last portion of the operative movement of the disk, thereby making it certain that a 15 record will have been printed and the bolt completely shifted before the lever is actuated. As will be apparent the engagement of the pin with the lever will move the lower end of the lever inward and move the 20 pawl 62 out of engagement with the ratchet wheel 61, thereby releasing the ratchet and, consequently, the key barrel and permitting the same to return to their normal positions. If desired a spring 68 may be interposed be- 25 tween the ratchet wheel and the frame member 2 to return the ratchet wheel and its co-operating parts to their normal positions.

The key-identifying type wheel 15 is controlled by the key. Preferably, however, the 30 key merely limits the movement of the type wheel and this movement is imparted to the type wheel by the knob 42. To this end the shaft 56 for the type wheel has rigidly secured to the end thereof, between the hollow shaft 49 and its extension 57, a controlling plate 69 which has on its inner surface a series of projections or teeth 70, these teeth being spaced step by step from the longitudinal edge of the extension or plate 40 69 and from the outer end of that plate and the several teeth being arranged at different radial distances from the axis of the shaft. This controlling plate may be secured to the shaft in any suitable manner, but as here 45 shown it is secured to a disk 71 which is secured to the end of the shaft. This disk is further provided with an arm 72 adapted to receive a stud 73 to which are connected two actuating rods 74 which serve to rotate 50 the shaft 59 and, consequently, the type wheel 15. The controlling plate 69 rotates with the shaft 56 and permits this rotation to continue until one of the projections on the plate engages the end of the key, which, 55 as above explained, is now held against movement.

Each key has its end differently constructed, as by varying the length thereof, so that no two keys will engage the same projection 60 of the controlling plate. Consequently, the type wheel 15 will be set in a different position for each key and a different indication will be printed on the record for each key when the lock is operated from the out- 65 side of the door, but when the lock is op-

erated from the inside of the door none of the key identifying marks will appear on the record, they having all been moved out of printing position by the return of the key barrel to its normal position. Thus, the 70 presence or absence of a key-identifying mark will indicate whether the lock was operated from the inside or the outside of the door. Of course, if desired, the identifying type wheel could be provided with a special 75 mark which would indicate when the lock was operated from the inside but this is not essential. The actuating rods 74 are connected with the shaft 43 so as to cause the type wheel to be moved by the rotation of 80 the shaft 43 in either direction. As here shown the shaft 43 has rigidly secured thereto arms 75 which project on opposite sides of the shaft and are provided near their ends with pins 76 and 77. Each of the connecting rods 74 is provided at its upper end with a seat 78 adapted to receive the adjacent pin 76 or 77. In order to support these seats always in a position to receive the pins the upper ends of the rods are connected with arms 79 loosely mounted on the shaft 43. Consequently, when the shaft 43 is rotated in either direction one of the pins 76 or 77 will be brought into engagement 90 with the seat of the adjacent rod 74 and this 95 rod moved downward to cause the shaft 56 to be rotated until one of the stops of the adjusting plate 69 comes in contact with the key. The pin carried by the other arm 75 will be lifted out of its seat without affecting the position of the arm 74. In order that the knob may complete its movement, after the movement of the identifying type wheel has been checked, each rod 74 is preferably formed in two parts slidably connected one to the other and having springs 100 80 interposed between the two parts thereof. The tension of these springs is sufficient to cause the movement of the type wheel but they will yield to permit the further movement of the shaft 43 after the movement of the type wheel has ceased. 110

Means may also be provided for indicating whether the bolt was moved into its locking position or its retracted position 115 when a given record was made. This may be accomplished by causing a record of one kind to be produced when the bolt is moved in one direction and causing a record of a different kind to be produced when the bolt 120 is moved in the other direction. To enable the different kinds of records to be produced we have provided the marking device 125 16, which may be in the form of a fixed type carrier having a single type and which is included in the record only when the bolt is moved in a given direction. In order that this type may print upon one movement only of the bolt we have made one of the platens, in the present instance 36, shorter 130

than the other so that on the outward movement of the bolt, when the platen 36 is operated, no record will be printed from the type on the carrier 16 but when the bolt is retracted the platen 37 will move across the type on the carrier 16, as well as the type on the other carriers, and will, therefore, print a record from this type which will indicate that this particular record as a whole was made while the bolt was being retracted. Of course, if desired, the type wheel 16 could be provided with two different marks and could be controlled by the movement of the bolt to shift one or the other of the types into printing position. In this connection it will be noted that after the movement of the bolt has been begun it must be completed before the bolt can be moved in the other direction, this being due to a full stroke mechanism and consequently, the bolt cannot be partly operated without making a record and then returned to its original position.

The operation of the mechanism will be readily understood from the foregoing description and it will be apparent that we have provided a simple, highly efficient recording device which will make a record of each movement of the bolt of the lock and will not only indicate when the bolt was operated but will indicate what key was used, whether the lock was operated from the inside of the door or the outside of the door and whether the bolt was moved into its locking position or its retracted position when the record was made.

While we have shown one embodiment of our invention it will be understood that this has been chosen for the purposes of illustration only and that we do not desire to be limited to the details of construction shown and described, for obvious modifications will occur to a person skilled in the art.

Having thus fully described our invention, what we claim as new and desire to secure by Letters Patent, is:—

1. In a device of the character described, a bolt, a recording device, a knob normally disconnected from said bolt and said recording device, and key-controlled means to operatively connect said knob with said bolt and said recording device.

2. In a device of the character described, a bolt, a recording device, a knob normally connected with said bolt and said recording device, a second knob normally disconnected from said bolt and said recording device, and key-controlled means to connect said second knob with said bolt and said recording device.

3. In a device of the character described, a bolt, a recording device, a knob normally connected with said bolt and said recording device, a second knob normally disconnected from said bolt and said recording device,

key-controlled means to connect said second knob with said bolt and said recording device, and means to indicate on said record which knob was actuated to make a particular record.

4. In a device of the character described, a bolt, a recording device, a knob normally connected with said bolt and said recording device, a second knob normally disconnected from said bolt and said recording device, key-controlled means to connect said second knob with said bolt and said recording device, and means to indicate on each record the direction in which the bolt was moved when said record was made. 70

5. In a device of the character described, a bolt, a recording device comprising type carriers, a roller platen movable across said type carriers, and a single device to actuate said bolt and impart operative movement to 80 said platen.

6. In a device of the character described, a bolt, a recording device comprising type carriers and a platen movable toward said type carriers, means for actuating said bolt 90 and said platen, two devices for imparting movement to said actuating means, and means for indicating on said record which of said two devices was used to actuate the bolt and recording device. 95

7. In a device of the character described, a bolt, adjustable type carriers, two platens, each mounted for movement across said type carriers, an operating shaft, means carried by said shaft for moving said bolt into either its locking or its retracted position and for actuating one of said platens when the bolt is moved in one direction and for actuating the other platen when the bolt is moved in the other direction. 100

8. In a device of the character described, a bolt, adjustable type carrying devices, platens, levers carrying said platens and operable to cause either of said platens to move toward the type on said carriers, a 110 shaft, an actuating device carried by said shaft to impart movement to said bolt in either direction, said actuating device being adapted to actuate one of said levers when said bolt is moved in one direction and to 115 operate the other of said levers when the bolt is moved in the other direction.

9. In a device of the character described, a bolt, adjustable type carrying devices, platens, levers carrying said platens and 120 operable to cause either of said platens to move toward the type on said carriers, a shaft, an actuating device carried by said shaft to impart movement to said bolt in either direction, said actuating device being 125 adapted to actuate one of said levers when said bolt is moved in one direction and to actuate the other of said levers when the bolt is moved in the other direction, paper feeding devices, and means actuated by the 130

movement of either of said levers to operate said paper feeding devices.

10. In a device of the character described, the combination, with a bolt and a recording device, of a knob normally disconnected from said recording device, and key-controlled means to connect said knob with said recording device.

11. In a device of the character described, 10 the combination, with a bolt and a recording device, of a device operatively connected with said bolt and said recording device, a knob normally disconnected from said bolt and said recording device, and a key-controlled clutch for connecting said knob with that device which is operatively connected with said bolt and said recording device.

12. In a device of the character described, 15 the combination, with a bolt and a recording device, of an actuating device for said bolt and said recording device, a knob normally disconnected from said actuating device, and a key-controlled device for connecting said knob with said actuating device.

13. In a device of the character described, 20 the combination, with a bolt and a recording device, of an actuating device for said bolt and said recording device, said actuating device comprising a disk, a knob, a second disk connected with said knob and normally disconnected from the first mentioned disk, and key-controlled means for connecting said disks one to the other to enable said actuating device to be operated by said knob.

14. In a device of the character described, 25 the combination, with a bolt and a recording device, of an actuating device for said bolt and said recording device, said actuating device comprising a disk, a knob, a second disk connected with said knob and normally disconnected from the first-mentioned disk, each of said disks having a recess in the edge thereof, a connecting device to be moved into said recesses to connect said disks one to the other, and key-controlled means to actuate said connecting device.

15. In a device of the character described, 30 the combination, with a bolt and a recording device, of an actuating device for said bolt and said recording device, said actuating device comprising a disk, a knob, a second disk connected with said knob and normally disconnected from the first-mentioned disk, 35 disk, a bar mounted for movement toward and away from said disks, key-controlled means to impart movement to said bar, and a connecting device carried by said bar and adapted to be moved into operative relation 40 to said disks to connect said knob with said actuating device.

16. In a device of the character described, 45 the combination, with a bolt and a recording device, of an actuating device for said bolt and said recording device, said actuating de-

vice comprising a disk, a knob, a second disk connected with said knob and normally disconnected from the first mentioned disk, said disks having alined notches, a bar mounted for movement toward and away from said disks, a pin carried by said bar and adapted to be moved into said notches to connect said disks one to the other, and key-controlled means for actuating said bar.

17. In a device of the character described, 50 the combination, with a bolt and a recording device, of an actuating device for said bolt and said recording device, said actuating device comprising a disk, a knob, a second disk connected with said knob and normally disconnected from the first-mentioned disk, 55 said disks having alined recesses, a bar mounted for movement toward and away from said disks and held against lateral displacement, a pin mounted on said bar and adapted to be moved into said recesses by the movement of said bar to connect said disks one to the other, said bar having slots to permit of the movement of said pin relatively thereto, and key-controlled means for 60 actuating said bar.

18. In a device of the character described, 65 the combination, with a bolt and a recording device, of an actuating device for said bolt and said recording device, said actuating device comprising a disk, a knob, a second disk connected with said knob and normally disconnected from the first-mentioned disk, 70 said disks having alined recesses, a bar mounted for movement toward and away from said disks having a curved slot arranged near the peripheries of said disks, a pin mounted in said slot and adapted to be moved into the recesses in said disks by the movement of said bar to connect said disks one to the other and movable along said slot when said disks are rotated, and means 75 to impart movement to said bar.

19. In a device of the character described, 80 the combination, with a bolt and a recording device, of an actuating device for said bolt and said recording device, said actuating device comprising a disk, a knob, a second disk connected with said knob and normally disconnected from the first-mentioned disk, 85 said disks having alined recesses, a bar mounted for movement toward and away from said disks and having a curved slot arranged near the peripheries of said disks, a pin mounted in said slot and adapted to be moved into the recesses in said disks by the movement of said bar to connect said disks one to the other and movable along said slot when said disks are rotated, and means 90 to retain said pin in said recesses when said disks have been moved away from their normal positions.

20. In a device of the character described, 95 the combination, with a bolt and a recording device, of an actuating device for said 100

- 5 bolt and said recording device, said actuating device comprising a disk, a knob, a second disk connected with said knob and normally disconnected from the first-mentioned disk, said disks having alined recesses, a bar mounted for movement toward and away from said disks and having a curved slot arranged near the peripheries of said disks, a pin mounted in said slot and 10 adapted to be moved into the recesses in said disks by the movement of said bar to connect said disks one to the other and movable along said slot when said disks are rotated, and curved flanges mounted on a 15 fixed support near said disks, adapted to engage said pin and hold the same in recesses in said disks when the latter have been moved away from their normal positions.
- 20 21. In a device of the character described, the combination, with a bolt and a recording device, of an actuating device for said bolt and said recording device, a knob normally disconnected from said actuating device, 25 means to connect said knob with said actuating device, a bar to actuate said connecting means, and a key-operated cam to impart movement to said bar.
22. In a device of the character described, 30 the combination, with a bolt and a recording device, of an actuating device for said bolt and said recording device, a knob normally disconnected from said actuating device, means to connect said knob with said actuating device, a bar to actuate said connecting means, a key barrel, a shaft arranged in alinement with said key barrel and having an opening to receive the end of the key, whereby said shaft may be caused to rotate 40 with said key barrel, and a cam carried by said shaft to actuate said bar.
23. In a device of the character described, the combination, with a bolt and a recording device, of an actuating device for said bolt 45 and said recording device, a knob normally disconnected from said actuating device, means to connect said knob with said actuating device, a bar to actuate said connecting means, a key barrel, a shaft arranged in alinement with said key barrel and having an opening to receive the end of the key, whereby said shaft may be caused to rotate with said key barrel, a cam carried by 50 said shaft to actuate said bar, a detent to hold said cam against reverse movement, and means controlled by the movement of said disks to move said detent into its inoperative position.
24. In a device of the character described, 55 a knob, a recording device comprising an adjustable type-carrying member, a connection between said knob and said type-carrying member to cause the adjustment of the latter, and key-controlled means to control 60 said adjustment.
25. In a device of the character described, a knob, a recording device comprising an adjustable type-carrying member and operating mechanism, a connection between said knob and said type-carrying member to cause the adjustment of the latter, and key-controlled means to establish connection between said knob and said operating mechanism and to control the adjustment of said type-carrying member. 75
26. In a device of the character described, a knob, a recording device comprising an adjustable type-carrying member, a connection between said knob and said type-carrying member for adjusting the latter, a series of stops carried by said type carrying member, and means for supporting a key in a fixed position to be engaged by one of said stops and limit the movement of said type-carrying member. 80
27. In a device of the character described, a knob, a recording device comprising an adjustable type-carrying member, a connection between said knob and said type-carrying member for adjusting the latter, a series of stepped projections connected with and rotating with said type-carrying member, and a key barrel, said key barrel being so arranged with relation to said projections that keys of different lengths inserted in 90 said barrel will be engaged by different projections and will cause different movements to be imparted to said type-carrying member. 95
28. In a device of the character described, the combination, with a bolt, a recording device, and an actuating device for said bolt and said recording device, of a knob normally disconnected from said actuating device, a key barrel, and key-controlled devices 100 to establish the connection between said knob and said actuating device, an adjustable type-carrying member having a series of stops connected therewith, and an operative connection between said knob and said 105 type-carrying member, said stops being so arranged with relation to said key barrel that when a key has been inserted in said key barrel to establish an operative connection between said knob and said actuating 110 device, said key will extend into the path of one of the stops of said type-carrying member. 115
29. In a device of the character described, the combination, with a bolt and a recording 120 device, said recording device comprising an adjustable type-carrying member having a series of stops, of a knob, a connection between said knob and said type-carrying member to cause said type-carrying member 125 to be moved in a single direction by the movement of said knob in either direction, and means for supporting a key in position to be engaged by one of said stops.
30. In a device of the character described, 130

- a bolt, a recording device comprising an adjustable type-carrying member, a knob adapted to be operatively connected with said bolt, and means actuated by said knob for imparting movement to said type-carrying member, and key-controlled means for limiting the movement of said type-carrying member.
31. In a device of the character described, 10 a bolt, a recording device comprising an adjustable type-carrying member, a knob adapted to be operatively connected with said bolt, means for adjusting said type-carrying member comprising a rock shaft, 15 connecting rods secured to said rock shaft, and connections between said connecting rods and said knob to cause said rock shaft to be moved in the same direction by the movement of said knob in either direction.
32. In a device of the character described, 20 a bolt, a recording device comprising an adjustable type-carrying member, a knob adapted to be operatively connected with said bolt, means for adjusting said type-carrying member comprising a rock shaft, 25 connecting rods secured to said rock shaft, arms rigidly connected with said knob, extending on opposite sides of the axis thereof and adapted to engage the respective connecting rods to impart movement thereto.
33. In a device of the character described, 30 a bolt, a recording device comprising an adjustable type-carrying member, a knob adapted to be operatively connected with said bolt, means for adjusting said type-carrying member comprising a rock shaft, 35 connecting rods secured to said rock shaft, arms rigidly connected with said knob, extending on opposite sides of the axis thereof and adapted to engage the respective connecting rods to impart movement thereto, 40 and means for controlling the position of said rods relatively to said arms.
34. In a device of the character described, 45 the combination, with a bolt, a recording device comprising an adjustable type wheel having a series of stops, and an actuating device for said bolt and said recording device, a key, of a knob normally disconnected from said actuating device, a connecting device to establish connection between said knob and said actuating device, key-controlled means for actuating said connecting device, means for holding said key against movement after said connecting device has been actuated, a connection between 55 said knob and said adjustable type carrier to move one of said stops into engagement with said key, said connection being a yielding one to permit of the further movement of said knob, and means controlled by the further movement of said knob to actuate said detent and to release said key.
35. In a device of the character described, 60 the combination, with a bolt and a record- 65 ing device comprising a series of type wheels, of two platens adapted to move over the type on said type wheels, one of said platens being adapted to engage all of said type wheels and the other being adapted to engage a part only of said type wheels, and means for imparting operative movement to one of said platens when said bolt is moved in one direction and for imparting operative movement to the other of said platens when said bolt is moved in the other direction.
36. In a lock, the combination, with a bolt, a recording device, and key-controlled means to actuate said bolt and said recording device, of means to prevent the removal of the key after operative movement has been imparted thereto and before said bolt has made a complete movement in one direction.
37. In a lock, the combination, with a bolt, a recording device, and key-controlled means to actuate said bolt and to actuate said recording device after initial movement has been imparted to said bolt, of means to prevent the removal of the key after the initial movement has been imparted to said bolt and before said recording device has been operated.
38. In a lock, the combination, with a bolt, an actuating device for said bolt, and a key to control the movement of said actuating device, of means to prevent the removal of said key after the initial movement has been imparted to said bolt and before said bolt has completed its movement.
39. In a lock, the combination, with a bolt, an actuating device for said bolt, and a key having movement to control said actuating device, of means to prevent the removal of said key after operative movement has been imparted thereto and before said bolt has made a complete movement in one direction.
40. In a lock, the combination with a bolt, 110 a recording device and a key-controlled actuating device for said bolt and said recording device, of means to prevent the removal of said key after initial movement has been imparted to said actuating device 115 and before said recording device has been operated.
41. In a lock, the combination, with a bolt, actuating mechanism therefor, and a key to control the movement of said actuating mechanism, of means to prevent the removal of said key after initial movement has been imparted to said actuating mechanism, and before said bolt has made a complete movement in one direction.
42. In a lock, the combination, with a bolt, actuating mechanism therefor, and a key to control the movement of said actuating mechanism, of means to prevent the removal of said key after initial movement 120

has been imparted to said actuating mechanism and before said bolt has made a complete movement in one direction, and means controlled by the movement of said 5 actuating mechanism to release said key.

43. In a lock, the combination, with a bolt, actuating mechanism therefor, and a key to control the movement of said actuating mechanism, of means to prevent the 10 removal of said key after initial movement has been imparted to said bolt and before said bolt has made a complete movement in one direction, and a device actuated by said actuating mechanism to release said 15 key.

44. In a lock, the combination, with a bolt, actuating mechanism for said bolt, and means comprising a key-actuated device to control the movement of said actuating mechanism, of means to prevent said 20 key-actuated device from returning to its normal position after initial movement has been imparted thereto and before said bolt has made a complete movement in one 25 direction.

45. In a lock, the combination, with a bolt, a recording device, actuating mechanism for said bolt and said recording device, and means comprising a key-actuated 30 device to control the movement of said actuating mechanism, of means to prevent the return of said key-actuated device to its normal position after initial movement has been imparted thereto and before said 35 recording device has been operated.

46. In a lock, the combination, with an actuating device, and a key to control the movement of said actuating device, of means to prevent the removal of said key 40 after operative movement has been imparted thereto and before the operative movement of said actuating device has been completed.

47. In a lock, the combination, with an actuating device, and a key-operated member to control the movement of said actuating device, of means to prevent the return of said key-operated member to its normal position after operative movement 50 has been imparted thereto and before the operative movement of said actuating device has been completed.

48. In a lock, a bolt, a key to control the movement of said bolt, and means to prevent the removal of said key after initial movement has been imparted thereto and before said bolt has made a complete movement in one direction.

49. In a lock, a bolt, a key to control the movement thereof, and means to prevent the removal of said key after initial movement has been imparted to said bolt and before said bolt has made a complete movement in one direction.

50. In a lock, a bolt, a recording device,

a key to control said bolt, key-controlled means to cause the operation of said recording device after initial movement has been imparted to said bolt, and means to prevent the removal of said key after initial movement has been imparted thereto and before said recording device has been operated.

51. In a lock, an actuating device, a knob permanently connected with said actuating device, a second knob disconnected from said actuating device, and key-actuated means to connect said last-mentioned knob with the first-mentioned knob, whereby the manipulation of either knob will impart movement to said actuating device.

52. In a lock, a bolt, a recording device, key-controlled means to actuate said recording device, and means to prevent the removal of said key after initial movement has been imparted thereto and before the operation of said recording device.

53. In a lock, a bolt, a recorder comprising a movable member, an actuating device, two members for operating said actuating device to impart movement to said bolt in either direction, one of said operating members being capable of operative movement independently of the other, and means for imparting movement from said actuating device to the movable member of said recorder when said actuating device is operated to move said bolt in either direction.

54. In a lock, a bolt, a recorder comprising a movable member, an actuating device comprising an actuating member pivotally mounted between its ends and having parts on opposite sides of its axis arranged to actuate said bolt, two members for operating said pivoted actuating device, one of said members being operable independently of the other, and means for imparting movement from said pivoted actuating device to the movable member of said recorder.

55. In a lock, a bolt, a locking device to retain said bolt against movement, key-controlled means to move said locking device into an inoperative position and to actuate said bolt, and means to prevent the removal of the key after said locking device has been moved into an inoperative position and before said bolt has made a complete movement in one direction.

56. In a lock, the combination, with a bolt, means for locking said bolt against movement, a recorder, and key-controlled means for actuating said locking device to release said bolt and for imparting movement to said bolt and to said recorder, and means to prevent the removal of said key after said bolt has been released and before said recorder has been operated.

57. In a lock, an actuating device mounted for movement about a fixed axis and having parts extending on opposite sides of said

axis, a recording device, an operating member for said recording device having pivoted arms arranged in the paths of the respective parts of said actuating device, whereby said recording mechanism will be actuated when said actuating mechanism is moved in either direction.

58. In a recording lock, a bolt, a recording mechanism comprising a type carrying device and an impression taking device, and means controlled by the operation of said bolt to cause said recording mechanism to print a record of one kind when said bolt is moved in one direction and to print a record 15 of another kind when said bolt is moved in the other direction.

59. In a recording lock, a bolt, a recording mechanism comprising a type carrying device and an impression taking device, and 20 means for controlling the operation of one of said devices according to the direction of movement of said bolt to cause said recording mechanism to print a record of one kind when said bolt is moved in one direction and 25 to print a record of another kind when said bolt is moved in the other direction.

60. In a mechanism of the character described, a bolt movable into and out of locking position, a recording device comprising 30 a plurality of marking devices, and means to cause a record to be made when said bolt is moved in either direction and to cause one of said marking devices to be included in said record when said bolt is moved in one

direction and to be excluded from said record 35 when said bolt is moved in the other direction.

61. In a mechanism of the character described, a bolt movable into and out of operative position, a recording device comprising 40 marking devices, two platens individually operable to cause a record to be taken from said recording device, one of said platens being adapted to take a record from all of said marking devices and the other of said 45 platens being adapted to take a record from a part only of said marking devices, and means for imparting operative movement to one of said platens when said bolt is moved in one direction and for imparting operative movement to the other of said platens when said bolt is moved in the other direction.

62. In a lock, the combination with a bolt, actuating mechanism therefor, and a key-controlled device to control the movement of 55 said actuating mechanism and having parts coöperating to prevent the removal of the key from said key-controlled device after the latter has been actuated and before said actuating mechanism has been operated.

In testimony whereof, we affix our signatures in presence of two witnesses.

BERNARD H. ZIEHLER.
JAMES C. DAWLEY.
